UNITED STATES PATENT OFFICE.

BENJAMIN WEBER, OF BALTIMORE, MARYLAND, ASSIGNOR OF ONE-HALF
TO CHARLES DITTMAR, OF BALTIMORE, MARYLAND.

HANDLE FOR VALISES, PARCELS, TEAPOTS, &c.

SPECIFICATION forming part of Letters Patent No. 728,058, dated May 12, 1903.

Application filed September 17, 1902. Serial No. 123,693. (No model.)

To all whom it may concern:

Be it known that I, BENJAMIN WEBER, a citizen of the United States, residing at Baltimore, in the State of Maryland, have invented certain new and useful Improvements in Handles for Valises, Parcels, Teapots, and Like Articles, of which the following is a specification.

My invention relates to improvements in handles for valises, parcels, teapots, and like articles.

The object of the invention is to provide a handle which shall be strong and durable and at the same time simple in construction in order that it may be produced cheaply and, further, to provide a handle which may readily be attached or detached without the use of tools.

The invention is illustrated in the accompanying drawings, in which—

Figure 1 is a perspective view of one of my improved handles. Fig. 2 is a side elevation of the wire construction of the handle. Fig. 3 is a top view of the same. Fig. 4 is a perspective view of a modified form of wire construction, and Figs. 5 and 6 illustrate top views of two additional modifications of the wire construction.

In all the forms shown the wire construction is of a single piece.

Referring now to Figs. 1, 2, and 3, one end, *a*, of the wire starts in the form of a spring snap or tongue and then extends upward and forms a half-curved stretch *a'* to the center of the handle, where it is bent back or doubled to form a loop *a*². The wire then extends toward the starting-point, and the half-stretch *a*³ extends parallel with the half-stretch *a'*, and near the snap or tongue *a* said wire forms one side *b* of the hook *b'*. The wire then forms an arched curve *b*² and then down and up again to form the other side of the hook *b'*. Thus it will so far be seen that the arched curve *b'* is over the tongue *a*. After the hook *b'* is completed it will be seen by reference to Fig. 3 that the wire then forms a full stretch *c*, which extends from said hook *b'* entirely across to the opposite side, where it curves down and forms one side *d* of the hook *d'*, then forms an arched curve *d*² and down

again to form the other side *d*³ of said hook, and then extends up, forming the half-stretch *e*, and extends in a direction parallel with the stretches *c* and *e* and ends in the snap or tongue *f*. When the wire is thus formed, it is the basis of the handle, and the same is covered with any suitable or desirable material, such as leather *g*, and at each end of said leather sleeve is a ferrule *h*, having a slot *h'*, through which the snaps or tongues *a* and *f* pass and work freely.

In Fig. 4 the construction of the wire is exactly like that in Figs. 2 and 3, except the stretches *a'* and *e'*, which form the snaps or tongues *a* and *f*, are omitted and the ends *i* and *i'* are hooked together at the center.

In Fig. 5 the modification consists in overlapping the ends *j* and *j'* and providing each with a loop *j*² and *j*³, which are wrapped around the other two strands. In Fig. 6 the ends *k* and *k'* are merely overlapped, and these ends and the full stretch *c* are secured by a wrapping of wire *l*.

In the several forms illustrated in the drawings it will be seen that there are several features common to all. First, all the hooks are formed by an arched curve of the wire; second, all are provided with securing means at the center of the handle, and, third, all are provided with one full stretch *c* of wire extending from one hook *b'* entirely across to the opposite hook *d'*.

All the forms may have a suitable covering, although the covering may be omitted in some cases where the handle is to be made very cheap to enable merchants to give them away when attached to purchased articles.

Having thus described my invention, what I claim as new, and desire to secure by Letters Patent, is—

1. A handle of the class described comprising a wire having a continuous stretch, *c*, from one side to the other, said wire being formed into an arched hook at each end of said continuous stretch and then extending back parallel with said continuous stretch and the two ends secured together between said hooks.

2. A handle of the class described comprising a continuous or full stretch of wire hav-

ing a hook at opposite sides and provided with interlocking loops between said two hooks.

3. A handle of the class described comprising a continuous wire or full stretch having a hook at opposite ends and interlocking loops between said hooks and one end of said wire extending from the interlocking loops toward one of said hooks and the other end ¹⁰ of said wire extending from said loops toward the other hook.

4. A handle of the class described comprising a wire having a continuous or full stretch from one end to the other, said wire being ¹⁵ bent at each end of said continuous stretch to form an arched curved hook and a stretch extending from each of said hooks toward

the center where they interlock and an end of said wire extending to and coacting with each hook to form a snap or tongue. ²⁰

5. A handle of the class described comprising a continuous wire having a hook at opposite ends and also having interlocking loops between said hooks and an end of said wire extending down to each hook and forming a ²⁵ snap or tongue and a covering over said wire between the two hooks but leaving said hooks and snaps uncovered.

In testimony whereof I affix my signature in the presence of two witnesses.

BENJAMIN WEBER.
